UNITED STATES PATENT OFFICE.

WILLIAM TURNER, OF MOSCOW, IDAHO TERRITORY.

PUMP.

SPECIFICATION forming part of Letters Patent No. 412,435, dated October 8, 1889.

Application filed April 26, 1889. Serial No. 308,688. (No model.)

To all whom it may concern:

Be it known that I, WILLIAM TURNER, a citizen of the United States, residing at Moscow, in the county of Nez Perces and Territory of Idaho, have invented a new and useful Pump, of which the following is a specification.

This invention relates to that class of pumps in which the water is elevated by pneumatic pressure upon the surface of the body of water; and it has for its object to provide a pump of this class which shall be simple in construction and conveniently arranged for operation.

With these ends in view the invention consists in the improved construction and arrangement of parts which will be hereinafter described, and particularly pointed out in the claim.

In the drawings, Figure 1 is a vertical sectional view of a well having my improved pump applied thereto in position for operation. Fig. 2 is a horizontal sectional view taken on the line *x x* in Fig. 1. Fig. 3 is a vertical sectional view, on a larger scale, of the pump-cylinder.

The same letters refer to the same parts in all the figures.

A designates the well, the walls of which are bricked up in such a manner as to render them air-tight and the top of which is provided with a cap or cover *B*, which is so constructed as to render the well perfectly air-tight.

C is the pump-cylinder, which is mounted vertically in the top or cover *B*, and which is provided at its lower end with downward-extending brackets *D D*, connected by a cross-piece *E*. At the lower end of the cylinder is fitted an annular elastic packing-ring *F*, which bears against an elastic cushion *G*, resting upon the bracket *E*.

H is a piston which slides vertically in the cylinder *C*, and which is provided with a downwardly-opening valve *I*. The piston-rod *J* extends upwardly through the cylinder, and is connected at its upper end to a lever *K*, which is fulcrumed to the upper end of the pitman *L*, the lower end of which may be connected to a bracket *M*, extending laterally from the upper end of the cylinder; or the

pitman *L* may be pivoted to any convenient support.

N designates a vertical pipe extending through the cap or cover *B* and reaching nearly to the bottom of the well. The upper end of the pipe *N* has a goose-neck *O*, and it is provided with a stop-cock *P*, by means of which the flow of water may be regulated.

The operation of the device is as follows: By operating the piston *H* by means of the lever *K* air will be forced into the well above the water between the annular packing-ring *F* and the elastic cushion *G*, which will admit of air being forced into the well, while the expansion of the elastic cushion *G* against the packing-ring *F* will prevent the air escaping. The operation is continued until the air has been compressed to the greatest possible extent in the space above the water-line in the well. When the stop-cock *P* is opened, the pressure of the air upon the surface of the body of water will cause the latter to flow through the pipe *N* as long as any air-pressure exists in the well.

I do not wish to be understood as limiting myself to the herein-described lever mechanism for operating the pump-piston, as any other suitable mechanism may be used without departing from the spirit of my invention. Other details may also be altered, when desirable, in the construction of the device.

Having thus described my invention, I claim—

The combination of the pump-cylinder terminating above the water-level and having downwardly-extending brackets connected by a cross-piece, an elastic cushion mounted upon the said cross-piece and bearing against an annular elastic packing-ring at the lower end of the cylinder, and the vertically-moving piston fitting in the cylinder and having a downwardly-opening valve, substantially as herein described, and for the purpose specified.

In testimony that I claim the foregoing as my own I have hereto affixed my signature in presence of two witnesses.

WILLIAM TURNER.
